ATTORNEY.

UNITED STATES PATENT OFFICE.

LOUIS WOJIDKOW, OF BROOKLYN, NEW YORK.

DESIGN FOR A STAND FOR CHAFING-DISHES.

SPECIFICATION forming part of Design No. 26,433, dated December 22, 1896.

Application filed November 13, 1896. Serial No. 612,033. Term of patent 3½ years.

To all whom it may concern:

Be it known that I, LOUIS WOJIDKOW, a citizen of the United States, residing in Brooklyn, county of Kings, and State of New York, have invented and produced a new and original Design for Stands for Chafing-Dishes, of which the following is a specification, reference being had to the accompanying drawing, which shows the same in perspective.

The leading feature of my design consists of an upper and lower beaded ring joined to curved standards or legs, the lower portions of which are ornamented, as shown, and the upper portions made in the form of a wreath.

A represents an upper ring, and B a lower ring, beaded on their outer edges, as shown at *a*, and joined to standards C. These standards are curved, as shown, and have their upper portions made in the form of a wreath c, the lower ends terminating in feet d.

What I claim is—

The design for a stand for chafing-dishes, as herein shown and described.

LOUIS WOJIDKOW.

Witnesses;

F. S. KENNEDY,
R. O. JOHNSON.
